(57) **CLAIM**

The ornamental design for a chopsticks sheath, as shown.

DESCRIPTION

FIG. 1 is a perspective view of a chopsticks sheath showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view of the chopsticks sheath with two chopsticks being inserted therein.

The broken lines shown in FIG. 8 are for illustrative purposes only and form no part of the claimed design.
